UNITED STATES PATENT OFFICE.

MARTIN V. CORNICA, OF CHICAGO, ILLINOIS.

CIRCUIT-INTERRUPTING MECHANISM.

Application filed April 20, 1921. Serial No. 462,884.

To all whom it may concern:

Be it known that I, MARTIN V. CORNICA, a citizen of the United States, and resident of Chicago, in the county of Cook and State 5 of Illinois, have invented a certain new and useful Improvement in Circuit-Interrupting Mechanism, of which the following is a full, clear, concise, and exact description, reference being had to the accompanying drawing, forming part of this specification.

My invention relates to circuit interrupting mechanism and is embodied in a plug and socket structure for attachment in any usual form of electric light socket, and is 15 arranged to receive an electric light bulb of usual construction.

The object of my invention is to provide a unitary structure of a form which can be readily inserted in an electric light socket 20 and which can be adjusted to positively open and close one or more circuits periodically at adjustable rates to flash or wink the electric lamps included in the circuit or circuits extended through the device.

Another object of my invention is to provide a device with mechanism for maintaining an electric circuit completely open and completely closed at a pair of contacts throughout substantially equal periods in 30 the vibratory action of the device so that the period of circuit closure will of certainty be of sufficient length to illuminate the lamp filaments, and so that the period of circuit interruption will be of certainty of sufficient 35 length to permit the lamp filament illumination to disappear.

Another object of the invention is to provide a simple form of periodicity adjustment so that the same device may be used 40 for flashing lamps at different rates, lamps having finer wire filaments being adaptable to higher frequencies than those having heavier wire filaments.

Another object of my invention is to so 45 organize the parts of this device that the device may be operated either hanging vertically or lying on its side.

A still further object of my invention is to provide a pivotal and frictional support 50 for the movable electric contact, the friction and current conductivity of which movable contact support will not materially alter to wear.

Other objects of the invention will appear 55 from the following specification and claims.

My invention is illustrated in the accompanying drawing in which—

Figure 1 is a plan view of the assembled structure;

Figure 2 is an elevation of the structure 60 with cover removed;

Figure 3 is a view looking at the structure from beneath with cover removed;

Figure 4 is a section taken on line 4—4 of Figure 3 in the direction of the arrows; 65

Figure 5 is a schematic circuit drawing of the device; and

Figure 6 illustrates the method of applying the device for the operation of the 70 Christmas tree lamps.

In carrying out my invention, I preferably connect the shell 10 of the plug with the sleeve 11 of the socket through a rigid metallic conductor 12, which, together with the insulating strip 13 and instrument board 75 14, constitutes rigid attachment means for the plug and socket bases 15 and 16 respectively.

Attached to the central conducting portion 18 of the plug is an angle plate 19 80 carrying a flexible contact spring 20, to the free end of which a tungsten contact 21 is attached. Mated with the contact 21 is a second tungsten contact 22 mounted upon the plate 23, which is held in frictional surface contact with a conducting plate 24 by means of a needle point 25 adjustably held in place by the spring clip 26. The conducting plate 24 is electrically connected with the extension plug terminal 28 by 85 means of a conductor 29, the terminal 28 being in turn connected through conductor 30 and the coil of electromagnet 31 with the center terminal 32 of the socket. A forked bracket 33 mounted upon the instrument 90 board 14 carries the armature 35 between prick punch depressions, the armature being provided with pointed pivots 36 so that it operates freely. The movable end of the armature carries a pair of fingers 38 and 100 39 adapted in the two positions of the armature to engage the spring wire 40 carried by the movable plate 28. When the armature is attracted by the magnet, the finger 38 engages the spring 40, rotating the plate 23 105 in a clockwise direction about its pivot 25 and thus separating the contacts 21 and 22 and interrupting the electric circuit. The circuit being interrupted at contacts 21 and 22, the armature is released, and the finger 110

39 engages the spring wire 40 and rotates the plate 23 in a counter-clockwise direction until the contacts 21 and 22 are re-connected, thus again establishing the circuit. The 5 periodicity of the device may be altered by shifting the stop 41 which is carried upon a screw 42 in a manner permitting of ready adjustment. The magnet 31 is supported by a bracket 44 in a manner which permits 10 the adjustment of the end of the magnet nearer to or further from the armature 35, which adjustment may also be used to aid in timing the periodicity of the device.

A spring extension terminal 45 is in electrical connection through conductor 46 with the conducting member 12 so that the contacts 28 and 45 may be used through the agency of an extension plug 48 for controlling an auxiliary circuit, such as the Christmas tree circuit shown in Figure 6, the current for this circuit not being carried through the coil of the electromagnet 31. The device is preferably constructed so as to operate satisfactorily on the amount of 25 current used in an ordinary 25 watt incandescent tungsten filament lamp. The auxiliary circuit, however, may contain lamps or other devices requiring much more current than that for the operation of a single lamp, the 30 only limit being the amount of current satisfactorily interrupted at the tungsten contacts 21 and 22. The device is preferably provided with a cover member 50, adapted to be sprung onto the edge of the insulating 35 strip 13, which may conveniently be provided with depressions for the receipt of projections 51 and 52.

It will be noted that in the operation of this device, the contacts 21 and 22 are maintained closed through the slight follow-up action of the contact 21 which is supported upon the spring 20. This insures a contact pressure throughout the closure of the circuit which pressure is controlled by the 45 degree of friction between the contact plates 23 and 24, this degree of friction being readily adjustable by means of the screw 27. It will be noted that through the angular arrangement of the coil 31, and its 50 armature, gravity will act upon the armature for retracting it from the magnet when the device is in either of two positions, that is, with the plug at the top or with the plug at one side. I have found it convenient to 55 mark the cover "This side up" and to so position the depressions 51 and 52 that the cover can only be put on in one way, thus indicating the proper position for operation when the device is laid on its side, as shown, 60 for example, in Figure 6.

Although I have shown and described my

device with respect to certain details, it is to be understood that these may be modified to some extent without departing from the spirit or scope of my invention. 65

What I claim is:

1. A device for inclusion in an electric light circuit having a plug at one end, and a socket at the other, comprising in combination a conducting member directly uniting 70 an element of the plug with an element of the socket, a pair of electric make and break contacts, and the coil of an electromagnet serially included in a circuit between a second element of the plug and a second element 75 of the socket, and a pair of branch circuit terminals, one connected to the first-mentioned elements of the plug socket, and the other connected to the conductor included between the other elements of the 80 plug and socket and connected to said conductor at a point between the electric make and break contacts and the coil of the electromagnet, and an armature for the electromagnet adapted to operate the electric 85 make and break contacts.

2. An attachment for electric light circuits having a plug at one end and a socket at the other, and comprising in combination an electrical conductor connecting one element of said plug with one element of 90 said socket, a pair of electric make and break contacts, and the coil of an electromagnet included in the second conductor connecting another element of said plug 95 with another element of said socket, a plate supporting one of said electric make and break contacts, and means to hold said plate frictionally in electrical contact with a conducting portion of the circuit included between the second element of the plug and socket, an extension from said plate, an armature for said electromagnet having a pair of fingers, one finger adapted to engage 100 said extension when the armature is attracted, the other finger adapted to engage said extension when the armature is released, the weight of the armature being sufficient to move said plate to unite said electrical contacts when one finger engages said extension, the armature being positioned diagonally to the axis of the structure so that 105 gravity will act upon the armature when the device is either in a vertical position or in one of its horizontal positions. 110

In witness whereof, I hereunto subscribe my name this 9th day of April, 1921.

MARTIN V. CORNICA.
